FUEL PUMP

Robert W. Erikson, Rockford, Ill., assignor to Sundstrand Machine Tool Co., a corporation of Illinois

Application February 28, 1952, Serial No. 273,810

8 Claims. (Cl. 103—42)

This invention relates to a pump and more particularly to a pump adapted for use with an oil burner for supplying fuel oil under pressure to the nozzle of the burner.

It is the general object of this invention to produce a new and improved oil burner pump.

It is a more specific object of the invention to produce an oil burner pump provided with burner shutoff valve means for controlling the flow of oil from the pump to the burner and so constructed and arranged as to reduce pulsations and fluctuations to a minimum.

Another object of the invention is to produce an oil burner pump of the type described in the preceding paragraph having means for adjusting the valve to open at various predetermined pressures which is easily operable and which is constructed to operate over a comparatively wide range of pressures.

A further object of the invention is to produce a two-stage oil burner pump in which a first-stage pumping means is used to draw oil from a supply tank to a reservoir and a second-stage pumping means is used to pump oil from the reservoir to the burner and in which there is provided a burner cutoff valve having bypass means for bypassing excess oil moved by the second-stage pumping means back to the reservoir, with the valve being designed so as to be easily adjustable to open at various pressures without being influenced by pressure conditions within the reservoir.

Yet another object of the invention is to produce a pump of the type described in the preceding paragraph in which the valve includes a bore having a piston valve slideable therein to divide the bore into a valve chamber, having a burner port controlled by the closed end of the piston valve, and a spring chamber in which there is located a spring for urging the valve toward closed position, together with sealing rings for preventing oil in the valve chamber or oil flowing through the bypass means from entering the spring chamber.

A further object of the invention is to produce a pump of the type described in the preceding paragraph which includes a drain port for draining oil which may leak past the sealing means and into the spring chamber.

Yet another object of the invention is to produce a pump as described in the preceding paragraphs in which the first-stage pumping means is provided with an inlet opening into the reservoir at the normal level of liquid therein so as to draw oil into the reservoir from a supply and to draw from the reservoir excess oil and air, and in which the discharge of the first-stage pumping means may be connected to the spring chamber of the valve to be drained therefrom through the drain port.

Other and further objects of the invention will be readily apparent from the following description and drawings, in which:

Fig. 1 is a longitudinal central section through a preferred form of the invention;

Fig. 2 is a section approximately along line 2—2 of Fig. 1; and

Fig. 3 is a diagrammatic view of the fuel circuit.

2

While this invention is susceptible of embodiment in many different forms, there is shown in the drawings and will herein be described in detail one specific embodiment, with the understanding that the present disclosure is to be considered as an exemplification of the principles of the invention and is not intended to limit the invention to the embodiment illustrated. The scope of the invention will be pointed out in the appended claims.

In the form chosen for the purposes of disclosure, the pump may comprise a two-part casing 10, 11, a first pumping device or means 12, a second pumping device or means 13, a drive shaft 14, a mechanical seal 15 for the drive shaft, a strainer 16 and a control valve mechanism 17. It is contemplated that the shaft 14 will be connected by suitable means to a driving motor (not shown) that the inlet port 18 will be connected to a source of fluid supply and the discharge port 19 to a burner nozzle. The casing parts are formed to provide a substantially cylindrical chamber in which the pumping devices 12 and 13 and strainer 16 are positioned and including a reservoir 20 to which the pumping devices are connected for the purposes hereinafter more fully described.

As illustrated herein the casing part 10 is in the form of a body member which is also used for supporting the fuel unit. Preferably this member is formed with supporting lugs 21 having bolt receiving apertures 22. The part 11 is in the form of a closure or cover and is bolted to the part 10 by the means of a plurality of screw devices 23.

The pumping devices 12 and 13 include end plates 24 and 25, an intermediate plate 26 and annular spacing members 27 and 28. The first-stage pump 12 comprises a roller or pinion 29 and an intermeshing toothed ring 30 which are operable in the chamber formed intermediate the plates 24 and 26. The second-stage pump 13 comprises a roller or pinion 31 and a toothed ring 32 operable in the chamber formed intermediate the plates 26 and 25. The rollers 29 and 31 are provided with driving pins 33 and 34 respectively which interengage with a keyway 35 in the drive shaft 14 when the pumping unit is assembled. A crescent 36 for the first-stage pump is secured to the plate 24 and a crescent 37 is secured to the intermediate plate 26 for the second-stage pump.

An inlet port 40 is drilled in the end plate 24 and extends through the periphery of the plate for supplying fluid to the first-stage pump. The intermediate plate 26 has an arcuate discharge cavity 42 which is connected with a channel port 43 formed in the plates 26, 28 and 25. Oil in the channel port 43 is directed into a chamber 44 by passage 44a which extends through the member 10 into a chamber 44b at the location of the seal 15 and thence into a passage 44c which connects with an annular recess 45 which is joined by a diagonally drilled hole 45a to a return port 46. The second-stage pump is provided with fluid from the bottom of the reservoir 20 through an inlet port 50 formed in the plate 26. Fluid from the second-stage pump passes through an outlet port 51 which communicates with a valve chamber 52.

In the form of the invention illustrated herein, the casing part 10 has an appendage portion 60 provided with a transversely extending bore 61. The valve chamber 52 is formed in this bore between the adjacent end of an end cap 62 which is screw-threaded into one end of the bore and a sleeve member 63 which is inserted into the central portion of the bore. If desired, a suitable gauge port 64 connected to the valve chamber 52 by passage 64a may be provided.

A hollow piston valve 65 is slidably mounted in the sleeve 63 so that the closed end 66 thereof will be subjected to the fluid pressure in the valve chamber 52. The piston valve 65 is provided with substantially cylindrical

side walls 67 and is open at its end opposite the end 66 to divide the bore 61 into the valve chamber 52 and a spring chamber 68. A coiled spring 69 bears at one end against the inner side of the bottom 66 of the piston and at the other end against a thrust washer 70 which in turn bears against an adjusting screw 71 screw-threaded into an end cap 72 which closes that end of the bore. A cap member 73 is provided with internal threads engaging the threads on a boss portion 74 integrally formed on the end cap 72, and a sealing ring 75 is adapted to be compressed between the cap 73 and the end cap 72 to seal off the spring chamber 68 from the atmosphere. Adjustment of the spring 69, of course, determines the pressure at which the valve opens.

Bypass means are provided for bypassing excess fluid moved by the second-stage pumping means 13. To provide such bypass, the piston valve 65 is arranged to uncover a bypass port 76 which is formed in the sleeve 63 and communicates with an annular recess 77 formed around the sleeve 63. This annular passage communicates with a bypass passage 78 which leads back to the reservoir 20. Formed in the portion of the sleeve 63 adjacent the valve chamber 52 is a plurality of passages 80 extending generally longitudinally of the sleeve, with each of the passages 80 being open at one end to the valve chamber 52 and at the other end to the interior surface of the sleeve at a point spaced inwardly from the end thereof. An annular groove 81 is formed on the exterior surface of the side walls of the piston valve 65 and is adapted to establish communication between the passages 80 and the bypass port 76 in the sleeve when the valve is opened by fluid pressure within the valve chamber. The degree of registry between the groove 81 and the port 76 depends, of course, upon the amount of movement of the piston valve 65 and hence the oil is variably bypassed depending upon movement of the piston valve which in turn depends upon the pressure of fluid within the valve chamber 52 and the setting of the spring 69. Bypassed excess fluid entering the bypass port 76 passes into the annular groove 77 and into a bypass port 82 which communicates with the bypass passage 78 to return such excess oil to the reservoir.

It will be noted from an examination of Fig. 3 that the inlet 40 of the first-stage pump 12 is connected to the reservoir 20 near the upper portion thereof. The location of the inlet port 40 is at the normal oil level, indicated at 90, within the reservoir and thus the first-stage pump serves in the first instance to draw oil into the reservoir from the inlet 18 and, after the reservoir has filled to the desired level, excess oil and air is removed therefrom by the first-stage pump. The inlet of the second-stage pump is connected to the reservoir below the normal level of liquid therein and thus receives oil by gravity flow to the inlet port 50. This particular arrangement of the inlet ports of the first and second-stage pumping means quite effectually removes air from the oil before it enters the inlet of the second-stage pump and thus prevents air from being entrained in the oil flow to the burner nozzle. A similar system is more fully described and claimed in the copending application of William Ray Kiefer filed on February 16, 1951 as Serial No. 211,244.

A further advantage of the system disclosed herein is the fact that excess oil pumped by the second-stage pumping means, which oil has already been freed from air by the operation of the first-stage pumping means, is returned to the reservoir, thus reducing the quantity of oil which must be drawn from the supply by the first-stage pumping means, thereby reducing friction losses in the feed line from the source of oil.

The open ended portion of the piston valve is provided with a pair of integrally formed rings 91 and 92 which serve to prevent leakage along the walls of the piston valve and into the valve chamber 68. Any leakage from the annular groove 81 past another integrally formed ring 93 which separates that annular groove from a second

annular groove 94, is led into the annular groove 77 through a drain port 95 for return to the reservoir. To prevent leakage from the valve chamber 52 or from the various bypass passages into the spring chamber, a pair of O-rings 96 and 97 are provided between the sleeve 63 and the bore 61. Minute quantities of oil which may leak past the seals just described and into the spring chamber may be drained therefrom through a port 98 formed in the sleeve which connects with the annular groove 45 and thence to the drain line 46.

To eliminate the number of ports required in the valve casing and to provide for a constant pressure in the spring chamber, the discharge from the first-stage pump through the outlet passage 44 is directed into the annular groove 45, to which, as previously noted, the port 98 is connected.

As has previously been indicated, adjustment of the compression of the spring 69 is by means of the adjusting screw 71. Inasmuch as the excess of fluid moved by the second-stage pump is directed back into the reservoir, it is clear that if the sealing means previously described were not provided to seal off the spring chamber 68 from the bypass system for the second-stage pumping means, the same vacuum conditions would exist within the spring chamber as exist within the reservoir 20. As the adjusting screw 71 does not provide an airtight seal, the cap 73 and seal 75 are provided. If the same vacuum conditions existed in the spring chamber as in the reservoir, removal of the cap 73 would disturb such vacuum condition during the adjustment of the screw and removal of cap 73 under such circumstances would actually cause the unit to be inoperative, that is, the flow of oil would cease, if reservoir 20 is under appreciable vacuum. Because of the fact that the spring chamber is sealed from the bypass means, no such difficulty in adjustment arises. Furthermore, variations in inlet pressure within the reservoir are likewise sealed from the spring chamber to eliminate variations in valve position because of variations of the pressure in the spring chamber caused thereby. Because of the further fact that the discharge from the first-stage pump is introduced into the spring chamber, a constant positive pressure exists therein. These features facilitate proper adjustment of the spring tension on the piston valve to fit the requirements of various operating conditions and also provide for stable operation of the valve.

I claim:

1. An oil burner pump having, in combination, a casing, a pumping means in the casing, a reservoir in the casing to which the inlet of the pumping means is connected, a bore in the casing closed at one end to form a valve chamber, an inlet port opening to said chamber and connected to the outlet of the pumping means, an outlet in the bore leading from said chamber, a piston valve slidable in said bore and controlling the outlet port, said valve having a closed end subject to the pressure of the fluid in said valve chamber and urged thereby toward open position, means positioned in the portion of the bore separated from the valve chamber by the piston valve for biasing said valve towards closed position, and bypass means for the valve including a bypass port opening into said bore at a point remote from the valve chamber, a bypass passage communicating at one end with the bypass port and at the other end with the reservoir, a passage in the casing constantly open at one end to receive a portion of the fluid in the valve chamber and opening at the other end to the bore at a point spaced inwardly from said valve chamber, passage means in the exterior surface of the piston valve and spaced from the closed end thereof and movable with said valve relative to said passage to control flow from said passage to said bypass port, and sealing means for sealing the portion of the bore separated from the valve chamber by the piston valve from the liquid in the valve chamber and from liquid

flowing through said bypass means in all operating positions of said piston valve.

2. An oil burner pump having, in combination, a casing, a pumping means in the casing, a reservoir in the casing to which the inlet of the pumping means is connected, a bore in the casing closed at one end to form a valve chamber, an inlet port opening to said chamber and connected to the outlet of the pumping means, an outlet in the bore leading from said chamber, a piston valve slidible in said valve chamber, said valve having a closed end subject to the pressure of the fluid in said valve chamber and urged thereby toward open position, means positioned in the portion of the bore separated from the valve chamber by the piston valve for biasing said valve towards closed position, and bypass means for the valve including a bypass port opening into said bore at a point remote from the valve chamber, a passage in the casing constantly open at one end to receive a portion of the fluid in the valve chamber and opening at the other end to the bore at a point spaced inwardly from said valve chamber, passage means in the exterior surface of the piston valve and spaced from the closed end thereof and movable with said valve relative to said passage to control flow from said passage to said bypass port, a bypass passage connecting the bypass port to the reservoir, sealing means for sealing the portion of the bore separated from the valve chamber by the piston valve from the liquid in the valve chamber and from liquid flowing through said bypass means in all operating positions of said piston valve and a drain port connected to the last mentioned portion of the bore for draining therefrom fluid leaking past the sealing means.

3. An oil burner pump having, in combination, a casing, a pumping means in the casing, a reservoir in the casing to which the inlet of the pumping means is connected, a cylindrical bore in the casing closed at one end to form a valve chamber, an inlet port opening to said chamber and connected to the outlet of the pumping means, an outlet port leading from said chamber, a cylindrical sleeve fixed in the bore, a hollow piston valve slidible in said sleeve and controlling the outlet port, said valve having a closed end and generally cylindrical side walls to define in said bore a spring chamber separated by the piston valve from the valve chamber and said valve being movable in response to the pressure in the valve chamber toward open position, a spring in the spring chamber and contacting the valve to bias the valve toward closed position, and bypass means for the valve including a bypass port opening into said bore at a point remote from the valve chamber, a bypass port in the sleeve communicating with the bypass port in the bore, a passage in the sleeve constantly open at one end to receive a portion of the fluid in the valve chamber and opening at the other end to the interior surface of the sleeve at a point spaced inwardly from said valve chamber, an annular groove in the exterior surface of the piston valve spaced from the closed end thereof and movable with said valve relative to said passage to control flow from said passage to said bypass ports, and sealing means for sealing the spring chamber from the liquid in the valve chamber and from liquid flowing through said bypass means.

4. An oil burner pump having, in combination, a casing, a pumping means in the casing, a reservoir in the casing to which the inlet of the pumping means is connected a cylindrical bore in the casing closed at one end to form a valve chamber, an inlet port opening to said chamber and connected to the outlet of the pumping means, an outlet port leading from said chamber, a cylindrical sleeve fixed in the bore, a hollow piston valve slidible in said sleeve and controlling the outlet port, said valve having a closed end and generally cylindrical side walls to define in said bore a spring chamber separated by the piston valve from the valve chamber and said valve being movable in response to the pressure in the valve chamber toward open position, a spring in the spring

chamber and contacting the valve to bias the valve toward closed position, bypass means for the valve including a bypass port opening into said bore at a point remote from the valve chamber, a bypass port in the sleeve communicating with the bypass port in the bore, a passage in the sleeve constantly open at one end to receive a portion of the fluid in the valve chamber and opening at the other end to the interior surface of the sleeve at a point spaced inwardly from said valve chamber, an annular groove in the exterior surface of the piston valve spaced from the closed end thereof and movable with said valve relative to said passage to control flow from said passage to said bypass ports, and a pair of O-ring seals between the sleeve and the bore and positioned on opposite sides of the bypass ports to seal the spring chamber from fluid passage through said bypass means.

5. An oil burner pump having, in combination, a casing, a pumping means in the casing, a reservoir in the casing to which the inlet of the pumping means is connected, a cylindrical bore in the casing closed at one end to form a valve chamber, an inlet port opening to said chamber and connected to the outlet of the pumping means, an outlet port leading from said chamber, a cylindrical sleeve fixed in the bore, a hollow piston valve slidible in said sleeve and controlling the outlet port, said valve having a closed end and generally cylindrical side walls to define in said bore a spring chamber separated by the piston valve from the valve chamber and said valve being movable in response to the pressure in the valve chamber toward open position, a compression spring in the spring chamber and contacting the valve to bias the valve toward closed position, means for adjusting the compression of the spring, means sealing said adjusting means from the atmosphere, bypass means for the valve including a bypass port opening into said bore at a point remote from the valve chamber, a bypass port in the sleeve communicating with the bypass port in the bore, means connecting the bypass port in the bore to the reservoir, sealing means for sealing the portion of the bore separated from the valve chamber by the piston valve from the liquid in the valve chamber and from liquid flowing through said bypass means and a drain port connected to the spring chamber for draining therefrom fluid leaking past the sealing means.

6. A two-stage oil burner pump having, in combination, a casing, a first-stage pumping means in the casing, a second-stage pumping means in the casing, a reservoir in the casing to which the inlet of the second-stage pumping means is connected, a supply tank connection leading to said reservoir, an inlet connection for the first-stage pumping means communicating with the reservoir to draw oil thereinto through the supply tank connection, a bore in the casing closed at one end to form a valve chamber, an inlet port opening to said chamber and connected to the outlet of the second-stage pumping means, an outlet in the bore leading from said chamber, a piston valve slidible in said valve chamber, said valve having a closed end subject to the pressure of the fluid in said valve chamber and urged thereby toward open position, means biasing said valve towards closed position, bypass means for the valve including a bypass port opening into said bore at a point remote from the valve chamber, a passage in the casing constantly open at one end to receive a portion of the fluid in the valve chamber and opening at the other end to the bore at a point spaced inwardly from said valve chamber, passage means in the exterior surface of the piston valve and spaced from the closed end thereof and movable with said valve relative to said passage to control flow from said passage to said bypass port, means connecting the bypass port to the reservoir, sealing means for sealing the portion of the bore separated from the valve chamber by the piston valve from the liquid in the valve chamber and from liquid flowing through said bypass means, a port in the last-mentioned portion of the bore connected to the outlet

of the first-stage pumping means, and means providing a drain for said portion of the bore to drain therefrom excess fluid pumped by the first-stage pumping means and fluid leaking past the sealing means.

7. A two-stage oil burner pump having, in combination, a casing, a first-stage pumping means in the casing, a second-stage pumping means in the casing, a reservoir in the casing to which the inlet to the second-stage pumping means is connected below the level at which the oil stands during normal operating conditions, a supply tank connection leading to said reservoir above the normal operating level of the oil therein, an inlet connection for the first-stage pumping means communicating with said reservoir at the normal oil level to enable the first-stage pumping means to withdraw excess oil and any air above said level, a cylindrical bore in the casing closed at one end to form a valve chamber and closed at the other end by cap, an inlet port opening to said chamber and connected to the outlet of the second-stage pumping means, an outlet port leading from said chamber, a cylindrical sleeve fixed in the bore, a hollow piston valve slideable in said sleeve and controlling the outlet port, said valve having a closed end and generally cylindrical side walls to define in said bore a spring chamber separated by the piston valve from the valve chamber and said valve being movable in response to the pressure in the valve chamber toward open position, a compression spring in the spring chamber and contacting the valve to bias the valve toward closed position, a screw device engaging threads formed in an opening extending through the cap for adjusting the compression of the spring, a seal for sealing the outer end of said opening and removable to permit adjustment of said screw device, bypass means for the valve including a bypass port opening into said bore at a point remote from the valve chamber, a bypass port in the sleeve communicating with the bypass port in the bore, a passage in the sleeve constantly open at one end to receive a portion of the fluid in the valve chamber and opening at the other end to the interior surface of the sleeve at a point spaced inwardly from said valve chamber, an annular groove in the exterior surface of the piston valve spaced from the closed end thereof and movable with said valve relative to said passage to control flow from said passage to said bypass ports, a passage connecting the bypass port in the bore to the reservoir, a port in the spring chamber connected to the outlet of the first-stage pumping means, sealing means for sealing the spring chamber from oil flowing through said bypass means, and means providing a drain for said spring chamber to drain therefrom excess fluid pumped by the first-stage pumping means and fluid leaking past the sealing means.

8. A two-stage oil burner pump having, in combination, a casing, a first-stage pumping means in the casing, a second-stage pumping means in the casing, a reservoir in the casing to which the inlet to the second-stage pump-

ing means is connected below the level at which the oil stands during normal operating conditions, a supply tank connection leading to said reservoir above the normal operating level of the oil therein, an inlet connection for the first-stage pumping means communicating with said reservoir at the normal oil level to enable the first-stage pumping means to withdraw excess oil and any air above said level, a cylindrical bore in the casing closed at one end to form a valve chamber and closed at the other end by a cap, an inlet port opening to said chamber and connected to the outlet of the second-stage pumping means, an outlet port leading from said chamber, a cylindrical sleeve fixed in the bore, a hollow piston valve slideable in said sleeve and controlling the outlet port, said valve having a closed end and generally cylindrical side walls to define in said bore a spring chamber separated by the piston valve from the valve chamber and said valve being movable in response to the pressure in the valve chamber toward open position, a compression spring in the spring chamber and contacting the valve to bias the valve toward closed position, a screw device engaging threads formed in an opening extending through the cap for adjusting the compression of the spring, a seal for sealing the outer end of said opening and removable to permit adjustment of said screw device, bypass means for the valve including a bypass port opening into said bore at a point remote from the valve chamber, a bypass port in the sleeve communicating with the bypass port in the bore, a passage in the sleeve constantly open at one end to receive a portion of the fluid in the valve chamber and opening at the other end to the interior surface of the sleeve at a point spaced inwardly from said valve chamber, an annular groove in the exterior surface of the piston valve spaced from the closed end thereof and movable with said valve relative to said passage to control flow from said passage to said bypass ports, a passage connecting the bypass port in the bore with the reservoir, a pair of O-ring seals between the sleeve and the bore and positioned on opposite sides of the bypass port in the bore to seal the spring chamber from fluid passing through said bypass means, a port in the spring chamber connected to the outlet of the first-stage pumping means and means providing a drain for said spring chamber to drain therefrom excess fluid pumped by the first-stage pumping means and fluid leaking past the sealing means.
